UNITED STATES PATENT OFFICE.

CHARLES B. WATERS, OF MONTCLAIR, NEW JERSEY.

AUTOMOBILE HEATER.

Application filed March 3, 1926. Serial No. 91,986.

The present inventions relate to automobile circulation and heating systems and more particularly the inventions comprise improvements in heating systems of the type shown in my copending Patent #1,575,667, issued March 9th, 1926 of which the present application is a continuation in part.

In the practical application of the heating system shown in my patent, I have discovered that the efficiency and effectiveness of the system may be considerably improved by properly proportioning the various areas, deflecting passages, and by specially proportioning and arranging the heater or radiating units.

An important improvement in the present invention over that shown in my above mentioned patent is effected by proportioning rearrangement of the deflecting and return openings in the coupling member between the heating and cooling system so that the distance between the outlet and return opening is reduced to a minimum. In this way the adverse head which must be overcome to maintain a circulation of hot water in the system is reduced and the rapidity of flow through the hot water heating system may be substantially increased. This increase of velocity of flow is important in its effect on the system as a whole, as it permits satisfactory heating with a reduced diversion of total flow in the cooling system.

A further decided improvement has been effected in the provision of a specially designed heater or radiating member in which a relatively small water space is provided in the heating units which are constructed of heavy masses of metal and with relatively large radiating surface areas in proportion to the volume of the water space, so that the heated water passes through the radiating members rapidly in a thin sheet and is robbed of its heat, and at the same time a minimum amount of water is deflected from the cooling system to effect the heating of the radiating members in satisfactory manner. By a proper design of the deflecting and radiating members, I have been able to reduce the total amount of deflection of water deflected from the cooling system to well below 20 per cent of the total circulation in the average force feed cooling system, and have been able to secure efficient and satisfactory heating with a diversion of water ranging from 1 to 10 per cent of the total circulation. Effective heating

of the usual closed type of automobile may be maintained with a diversion of approximately 8 per cent of the water in the circulating system. This diversion is so small that it has a negligible effect in the operation of the cooling system. With my improved deflecting arrangement and heating or radiating members, I have been able to reduce the size of connections and the diversion of water to such an extent that in order to maintain a satisfactory heating in cold weather, a control of the water temperature becomes essential for satisfactory operation. In the prior proposed systems, the diversion of water and restriction of the cooling effect in the systems has been such as to give trouble due to overheating of the engine, but with my present improvements the diversion of water from the cooling system is so small that means for raising the temperature in the average force feed cooling system in cold weather by the provision of adjustable radiator covers or other suitable temperature controlling means must be provided.

Accordingly, objects of the present invention are to provide an improved water heating system for automobiles and the like, in which the diversion of water from the cooling system is negligible while at the same time a high heating efficiency is maintained; to provide means for regulating the temperature in the cooling system to bring the water temperature to the point where satisfactory heating may be maintained; to provide novel water temperature and level indicating means; and to provide novel and ornamental water heater structures especially adapted for use in automobile heating.

Further objects of the invention are such as may be attained by the various combinations, sub-combinations, and principles more fully hereinafter set forth and as defined by the scope of the appended claims.

Referring to the drawings—

Figure 1 is a diagrammatic side elevation showing the general arrangement of one form of the invention.

Figure 2 is a sectional view showing the arrangement of an improved coupling member whereby the efficiency of operation of my improved systems is substantially improved.

Figure 3 is a plan view of a form of heater especially adapted for use in the invention.

Figure 4 is a sectional view taken along line A—A of Figure 3.

Figure 5 is a plan view of a modified form of heater especially adapted for use with my invention.

Figure 6 is a sectional view taken along line B—B of Figure 5.

Figure 7 is a fragmental sectional view along line C—C of Figure 5.

Figure 8 is a perspective view showing a modified form of heater arrangement and 10 combined foot rest especially adapted for use with the system of my invention.

As shown in Figure 1, 1 represents the engine of a motor vehicle, the upper part of the jacket space of which is connected by 15 means of the conduits or hose couplings 2 to the upper part of a cooling radiator 3. Cooling radiator 3 is connected in well known manner to atmosphere, and at its bottom is connected by means of coupling 4 to 20 a water circulating pump 5. Pump 5 is driven in any suitable manner from the engine and is connected by means of the coupling 6 to the lower part of the cooling jacket for the engine 1. As is well known 25 in the art, cooling water from radiator 3 is drawn through coupling 4 by the pump 5 and forced through coupling 6 into the engine cooling jacket and through return coupling back to the cooling radiator. Interposed in the connection 2 between the 30 engine 1 and the radiator 3 is a coupling member 7 made of suitable metal and provided with a main opening or passage 8 of such an area that the main circulation cooling system is not substantially restricted.

Formed in a branch 9 of the coupling member 7 is an outlet passage 10 and a return passage 11 for water deflected from the cooling system. A common wall 12 separates the passages 10 and 11 from each other and terminates in a projecting section 13 which protrudes into the main passage 8 to deflect a portion of the water flowing through the passage 8 in the direction shown by the arrow (Figure 2). The projecting section 13 is curved at 14 and 15 in the shape of parabola starting at "a" in a line parallel to the direction of flow of the water through the passage 8 and terminating at "b" in the surfaces of wall 12. The relation of the sectional areas of the passages 10 and 11 to each other and to the sectional area of the passage 8 is an important feature of the present invention. While cross-sectional areas of the passages 10 and 11 are preferably equal to each other and may range from approximately 1 to 25 per cent of the cross-sectional area of the passage 8, I have found that for most satisfactory operation 55 the sectional areas of the passages 10 and 11 should be below 10 per cent and above 1 per cent of the cross-sectional area of the passage 8. An excellent proportion in practice has been reached when the area of 60 the passages 10 and 11 respectively are equal

to about 2 per cent of the area of the passage 8.

The amount of protrusion and shape of the projecting section 13 of the wall 12 are proportioned so that the area of opening 70 at the mouths of the passages 10 and 11 communicating with the passage 8 are equal in area or preferably slightly greater than the cross-sectional area of the passages 10 and 11 and the openings at the mouths are as 75 close to each other as is possible.

To reduce the restriction of flow of water through the passage 8 by the projecting member 13 the area of the passage 8 is enlarged at 16 by providing an outward bulge 80 in coupling 7 around the projection 13 so shaped as to maintain the area of the passage 8 substantially uniform throughout the length of the coupling member 7.

Passage 10 extends downward through the 85 arm 9 and through a coupling projection 17, while the passage 11 is extended through a coupling projection 18 which protrudes beyond the end of the coupling projection 17 and is provided with a threaded section 19 90 upon which a control valve 20 is threaded. The control valve 20 may be of any usual type for stopping the flow of water through the passage 11 and is provided with a coupling section 21. The coupling sections 17 95 and 18 are inclined at an angle of approximately 45 degrees to the branch 9. This is an important feature of the invention as it permits the application of my improved system to any of the present well known 100 automobile cooling systems regardless of variation of the angle of couplings 2 without introducing reverse bends into the flexible hose couplings.

Secured to the coupling projection 17 is 105 a flexible hose connection 22 which at its lower end is connected to a heater control valve 23. Valve 23 is connected by means of a suitable connection 24 to the inlet opening of one of my specially constructed water 110 heaters 25. The outlet opening of the heater 25 is connected by means of a flexible hose connection 26 to the coupling section 21 of the valve 20. The hose connections 22 and 26 are of flexible material which acts as a 115 heat insulator preventing loss of heat from the water passing therethrough.

The proportions and construction of the heaters or radiating units used are of a type especially adapted for use in connection with my improved heating system. The heater arrangements are such as to provide a water space in the heater through which the water must pass in a wide sheet or stream which is as thin as practicable in commercial constructions. By this arrangement, a large amount of radiating surface is secured with a small volume of water space in which the water changes rapidly.

In the form of heater shown in Figures 120

3 and 4, a bottom casting 27 is provided on the lower surface thereof with a plurality of ribs 28 to increase the radiating surface and to strengthen the casting. Inlet connection 29 and outlet connection 30 for the water are provided. Casting 27 is secured to top casting 31 by means of the bolts 32 which pass through and secure a spacing gasket 33 in position to form the walls of a water space 34 between the plates 27 and 31. Gasket 33 is of sufficient thickness and of such shape as to give the desired cross-sectional area of the water space 34. Bolts 32 are of such a size and strength that in event the water in the heater freezes they will fracture due to the expansion of the ice before the castings 27 or 31 will break. To provide additional radiating surface and for strengthening top of the casting 31 the ribs 35 are provided on the upper surface thereof. Side members 36 are formed integrally with the top casting 31. Formed on the bottom edges of side members 36 are the openings or notches 37 for the admission of air to the bottom casting 27 of the heating unit when the heater is in position on the floor or foot board of an automobile. The sides 36 provide supports for the heater and at the same time improve the appearance thereof by covering the bottom plate and the spacing gasket construction. It will be noted in this form of heater the water will be forced through space 34 from the inlet opening 29 to the outlet opening 30 in a sheet or stream which may be one-quarter inch or less in depth and from which the heat will be transferred rapidly. A small amount of continuously changing hot water is continuously forced through the heater which will accordingly warm up rapidly. Because of the mass of metal utilized, the heat will be retained for a substantial period of time after the flow of hot water has ceased so that the car will be heated after the engine has been stopped for a substantial period of time.

The form of heater shown in Figures 3 and 4 is especially adapted for location between the seats of a car to be heated. When it is desired to place the heater on the inclined foot-board of an automobile to heat the front of the machine, the form of heater shown in Figures 5, 6, and 7 is preferably utilized. In this form of heater the lower and upper castings 27 and 31 are made substantially square in shape and a rib or dividing member 39 is formed integrally with and diagonally across the upper surface of the casting 27. The rib 39 is centrally grooved and nesting in the groove is a compressible packing member 40 preferably of a strip of rubber circular in cross-section, against which the lower surface of the upper casting 31 is pressed by means of the bolts 32 when the unit is assembled. The rib 39 and strip 40 divide water space 34 into sections 41 and 42. In this form of the invention the inlet connection 29 for the heated water is formed at the upper right hand corner of the section 41 adjacent the partition 39, and the outlet for the water is formed on the opposite side of the partition 39 in section 42 adjacent the inlet 29. With this arrangement the connections to the inlet 29 and outlet 30 at the right hand side of the inclined foot-board of an automobile in a position clearing the exhaust pipe of the engine as ordinarily disposed. Heated water passing inward through the connection 29 is compelled to circulate in a long path as indicated by arrows in Figure 5 through section 41, around the end of the partition 39, and through section 42 to the outlet opening 30.

In the form of heater shown in Figure 8, the side member 36 for the elongated heating unit as shown in Figures 3 and 4 is shaped so that when the heater rests on the floor of a machine or automobile, top casting 31 will be inclined and will serve as a foot rest heater.

It will be understood that any one of the forms of heaters described may be used at 25 in Figure 1. To provide for a suitable control of the temperature of water in the cooling system, a radiator cover 43 of any well known type is provided which may be adjusted to provide a suitable water temperature in the cooling system for effective heating as weather conditions vary.

In operation of the form of invention so far described, the heated water from the engine is circulated through the passage 8 of the coupling member 7. As the water passes projecting section 13, the velocity of flow will build up a circulating pressure in the passage 10 and will exert a suction on 105 the mouth of passage 11. The combined pressure and suction action will be ample to force the heated water at a relatively rapid rate downward through passage 10 and hose connection 22 to the heating unit 25 and 110 back through the hose connection 26, passage 11 into the circulating system, against the natural tendency for the heated water to rise and against the difference in head of the column of water in passages 10 and 11 and 115 connections 22 and 26. In the heater 25 the water will be robbed of its heat and the heat will be radiated into the space to be heated.

What is desired to be secured by Letters 120 Patent and claimed as new is:

1. An automobile radiator comprising spaced plates, a thin compressible gasket forming the side walls of a water receiving chamber arranged between said plates, a wall projecting into said chamber and extending from one side wall across the chamber to a point spaced from another wall, a yielding packing between said wall and the overlying plate, and means to clamp said plates together said means serving to com- 125

press said gasket and packing to form water tight joints.

2. An automobile radiator including a plate flanged on all sides, a second plate arranged within said flanges, a thin compressible gasket spacing said second plate from the body of the first named plate providing a water circulating space between said plates, said flanges being provided with openings and the second plate being provided with heat radiating ribs on its outer surface.

3. An automobile heating radiator utilizing the water of the automobile engine cooling system comprising a supporting casing having a top portion provided with depending supports projecting downwardly from said top portion to space said top portion from the floor of the automobile, said supports being arranged in lateral spaced relation so as to permit the circulation of air beneath said top portion, a plate substantially coextensive with said top portion and arranged in slightly spaced relation thereto to provide a water circulating chamber of small depth and relatively great width, an inlet and an outlet in said plate arranged in position to cause the water to circulate through said chamber.

4. An automobile heating radiator utilizing the water of the automobile engine cooling system comprising a supporting casing having a top portion and depending supports spaced laterally from each other to provide for the circulation of air beneath said casing, a plate suspended from said top portion in slightly spaced relation thereto, and forming with the under surface of said top portion a water circulating space designed to cause the circulation of water in a stream or streams of relatively small depth and an inlet and an outlet communicating with said space and positioned to cause circulation through said space.

5. An automobile heating radiator utilizing the water of the automobile engine cooling system comprising a supporting casing having a top portion provided with heat radiating means, and portions projecting downwardly from said top portion to support said portion in spaced relation to the floor of an automobile body, said portions being spaced laterally to permit the circulation of air beneath said top portion, a plate suspended from said top portion in slightly spaced relation to the under surface of said top portion and forming therewith a water circulating chamber of relatively great width and small depth whereby the water will be caused to traverse said chamber in thin sheets, an inlet and an outlet in said plate communicating with said chamber and heat radiating ribs projecting from the outer surface of said plate.

6. An automobile heating radiator utilizing the water of the automobile engine cooling system comprising a supporting casing having a top portion provided with heat radiating means, and portions projecting downwardly from said top portion to support said top portion in spaced relation to the floor of an automobile, said portions being spaced laterally to permit the circulation of air beneath said top portion, a plate suspended from said top portion in slightly spaced relation to the undersurface of said top portion and an open rectangular gasket arranged between said plate and said portion, and means to clamp said plate, gasket and top portion together forming a water receiving chamber of relatively great width and small depth, and an inlet and outlet in said plate disposed in position to cause a circulation of water in said chamber.

7. An automobile heating radiator utilizing the water of the automobile engine cooling system comprising a casing having a top, sides and ends, the bottom of said casing being open, means to support the body of said casing in spaced relation to the floor of an automobile body with said open bottom facing said floor, said means being formed to provide air passages opening in said casing to permit relatively free circulation of air around said supporting means and in the casing, and means within said casing designed to conduct the heating water in a stream of very small depth beneath said casing.

8. An automobile heating radiator utilizing the water of the automobile engine cooling system comprising a casing having a top, sides, ends and an open bottom, said casing being provided with means to support it on the floor of an automobile, said means being formed to bodily space the casing from said floor so that air is free to circulate to and through said open bottom, means arranged within said casing to cause the circulation of water in thin sheet-like streams, said means being provided with heat radiating ribs.

9. An automobile heating radiator utilizing the water of the automobile engine cooling system comprising a casing having a top, sides, ends and an open bottom, means to support said casing with the open bottom thereof facing but spaced from the floor of an automobile body, said means being so formed as to provide a relatively free circulation of air to and through said open bottom, means arranged within said casing to cause the circulation of water underneath in very shallow streams, and ribs to radiate the heat from said water to the space within said casing.

In testimony whereof I affix my signature.
CHARLES B. WATERS.
